UNITED STATES PATENT OFFICE.

ANTHONY VAN WAGENEN, OF SIOUX CITY, IOWA, ASSIGNOR, BY MESNE ASSIGNMENTS, TO CLARK AUTOMATIC TELEPHONE SWITCH-BOARD COMPANY, OF PROVIDENCE, RHODE ISLAND, A CORPORATION OF WEST VIRGINIA.

TRANSMITTER.

No. 804,279.

Specification of Letters Patent.

Patented Nov. 14, 1905.

Application filed April 30, 1896. Serial No. 589,739.

To all whom it may concern:

Be it known that I, ANTHONY VAN WAGENEN, a citizen of the United States, residing at Sioux City, in the county of Woodbury and State of Iowa, have invented certain new and useful Improvements in Transmitters; and I do hereby declare the following to be a full, clear, and exact description of the invention, such as will enable others skilled in the art to which it applies to make and use the same.

My invention relates to improvements in instruments designed for use in connection with systems of electrical intercommunication, such as automatic telephone-exchange systems; and it consists in the improved transmitter, the construction and arrangement of the parts of which will be hereinafter fully described, and particularly pointed out in the claims.

The object of my invention is to provide a simple, compact, and cheap transmitter which will not readily get out of order and which can be easily operated by inexperienced persons.

In accomplishing the object of my invention I provide a revolute circuit making and breaking wheel against the periphery of which presses a spring-actuated contact-piece in suitable connection with the outside circuit. In connection with the wheel I use a dial-plate having thereon the names, numbers, or other designations of the connections which it is desired to establish or the signals which it is desired to give by the use of the transmitter and also a series of apertures, one for each such name or other designation, into which plugs are adapted to be inserted, so as to arrest the movement of the circuit making and breaking wheel by engagement with a stud or stop projecting from the upper surface of the same.

The power required to actuate the circuit making and breaking wheel is produced by the action of a spring which is secured at one end to the shaft on which the circuit making and breaking wheel is mounted and at the other end to the case which incloses said wheel. Power is stored in the spring by revolution of the circuit making and breaking wheel in a direction opposite to that in which said wheel moves when making the electrical contacts necessary to bring about any desired connection. As it is thus necessary in my present construction to impart the

power required to cause movement of the circuit making and breaking wheel by manual rotation of said wheel, I have found it expedient to use a switch operated directly by the circuit making and breaking wheel itself to break the circuit through the transmitter when the circuit making and breaking wheel is moved in the direction required to store power in the operating-spring and to make the circuit when the return movement of the circuit making and breaking wheel commences. In order that the switch may be operated correctly, I further provide means for making it necessary to revolve the circuit making and breaking wheel through a complete revolution when power is being stored before the return movement of such wheel can commence. I thus gain the additional advantage of insuring the return of the circuit making and breaking wheel to its normal or zero position at the close of each actuation thereof. In this manner it is rendered unlikely that the connection established or signal given will be continued after the use of the service instrument has been concluded, as the mere withdrawal of the indicator-plug will allow the circuit making and breaking wheel to return to its normal position.

My invention is fully illustrated in the drawings which accompany and form a part of this application, in which the same reference-letters refer to the same or corresponding parts, and in which—

Figure 1 is a top plan view of my transmitter, a portion of the case of the same being broken away to show the circuit making and breaking wheel and the mechanism in connection therewith. Fig. 2 is a side elevation of my transmitter with the outer case broken away. Fig. 3 is a detail perspective view of the switch mechanism by means of which the circuit through the transmitter is made and broken at each actuation of the circuit making and breaking wheel, also showing the pawl which insures the complete revolution of the circuit making and breaking wheel at each rotation of the same designed to store power in the power-spring.

Referring to the drawings, A represents the case. This case may be of any suitable material, but is preferably made of nickel-plated metal, so as to give the same a neat and at-

tractive appearance. The case is provided with a bottom or bed plate B, from the center of which projects upward the central shaft C. Upon the shaft C is mounted the circuit making and breaking wheel D. Said shaft may be rotated in one direction against the tension of a spring G by means of a knob F. Rotation in the opposite direction is accomplished by the said spring, one end of which is secured to the shaft, the other end being secured to a base-plate H, supported upon the bottom or bed plate B of the case. Rotation of the shaft under the influence of the spring is controlled by an escapement mechanism E, which is held in place through being connected to the dial I and through having a bearing orifice through which shaft C passes.

The top of the case A is closed by the dial I, on which are formed in regular series the names, numbers, or other designations of the connections which it is desired to establish or the signals which it is desired to give by the use of my transmitter and also a series of apertures corresponding to the several designations. Into these apertures plugs K are adapted to be inserted, so as to arrest the movement of the circuit making and breaking wheel by engagement with the stop d, which projects from the upper surface of the same. The circuit making and breaking wheel D, which, as before stated, is mounted upon the central shaft C and operated by the action of the power-spring G, is formed with a series of teeth, cogs, or projections upon its periphery corresponding in number to the number of names or other designations upon the surface of the dial or the maximum number of subscribers in the system. With the periphery of the circuit making and breaking wheel D engages the spring-pressed contact-lever L, the lower end of which is pivotally mounted upon a bracket l, projecting from the side of the case A. The spring l, which controls the position of the contact-lever L, bears against an insulated plate l², which is secured to the side of the case. The bracket l, which serves to support the contact-lever L, is mounted upon an insulated base-plate l³, as shown, so that the contact-lever L is insulated from the case, except in so far as it contacts with the circuit making and breaking wheel D. The contact-lever L is connected to the binding-post N through the wire l⁴, the switch-lever M, and the wire l⁵. By means of the binding-post N any desired connection with an outside circuit can be established. The circuit making and breaking wheel D forms of itself the other branch of the circuit, as it is not insulated from the case A, and the case A is provided with a binding-post N', by means of which it may be placed in any desired circuit. It will thus be apparent that when the connection of the contact-lever L to the binding-post N is complete the passage of every tooth of the circuit making and break-

ing wheel D past such contact-lever will cause a breaking and making of the circuit and will serve to actuate the receiver or other device with which the transmitter may be in electrical connection.

The method of operation of the switch m is as follows: In my transmitter the electrical contacts which it is the function of the circuit making and breaking wheel to make are formed during the backward movement of the circuit making and breaking wheel D to its normal or zero position after such circuit making and breaking wheel has been rotated forward through a complete revolution in order to enable the power-spring G to store sufficient power to operate the same. It is apparent, therefore, that in order to prevent the registering of a double series of contacts by the movement of the circuit making and breaking wheel provision must be made for keeping the circuit broken during the movement of the circuit making and breaking wheel, which has for its purpose the storage of power in the spring G and for completing the circuit to the contact-wheel D and lever L when the backward movement of the circuit making and breaking wheel takes place. This is accomplished by the following construction: The switch-lever M is pivotally mounted upon an insulated base M'. The switch-lever is in the form of a bell-crank lever and is formed with an arm of insulating material m and with an arm of conducting material m'. Stops m² and m³ serve to limit the pivotal movement of the switch-lever. When the switch-lever is in the position shown in the drawings, the arm m' of the same does not contact with the contact-point m⁴, and thus the circuit to the contact-lever L is broken, and movement of the circuit making and breaking wheel in the direction of the arrow in Fig. 1 can take place without making any electrical contacts which will operate the receiver or other device with which the transmitter may be in electrical communication. When the circuit making and breaking wheel has been rotated through an entire revolution, however, the stop d', which is formed on the lower surface of the same, will engage with the arm m of the switch-lever M and will move such switch-lever pivotally until the arm m' of the same contacts with the contact-point m⁴, and thus establishes the connection from the outside circuit to the switch-lever L, and thereby through the transmitter. As the backward movement of the circuit making and breaking wheel now takes place, electrical contacts will be made as each tooth of such wheel passes the contact-lever L, and the receiver or other instrument in electrical communication with the transmitter will be properly actuated to establish the desired connection or set the desired signal. The movement of the circuit making and breaking wheel may be arrested at any point by the insertion of the

indicator-plug K in any one of the apertures formed in the dial, and upon the simple removal of the indicator-plug the circuit making and breaking wheel will return to its normal or zero position by the actuation of the power-spring G without any further operation by the operator.

In order to insure the circuit making and breaking wheel being moved through a complete revolution each time that power is being stored in the power-spring G, and thereby the proper operation of the switch-lever M, I increase the distance between two of the cogs d^2 and d^3 on the circuit making and breaking wheel and provide a locking-pawl O, pivotally supported from any convenient portion of the frame of the instrument—as, for example, the top plate I—said pawl arranged to engage the teeth of wheel D and of such width and length that it can be reversed only when within the said wide space of the wheel. Said pawl, therefore, acts to prevent reversal of movement of the wheel D in whichever direction such wheel may have started, until, the movement being complete, the wide space of the wheel is opposite said pawl, so that the latter may be reversed by movement of the wheel in the reverse direction. When, therefore, the circuit making and breaking wheel is revolved in a direction to cause power to be stored in the power-spring G, it will be impossible for any return movement of the circuit making and breaking wheel to take place until such wheel has been turned through a complete revolution, the pawl O has again slipped into the enlarged space provided therefor, and, as a necessary result, the switch mechanism M has been properly actuated to close the circuit through the transmitter. The power thus stored in the power-spring is sufficient to cause the return movement of the circuit making and breaking wheel through a complete revolution, so that the circuit through the transmitter is broken at the close of each actuation thereof.

The escapement mechanism E, which serves to regulate the speed of rotation of the circuit making and breaking wheel, is formed as follows: Upon the central shaft C is mounted the main wheel e of the escapement mechanism, such gear-wheel being rigidly connected with the circuit making and breaking wheel, so as to move with the same. Upon the central shaft is also mounted a frame e' , which forms a support for the escapement-wheel e' , (which is geared with the gear-wheel e by means of the pinion e^3 , mounted upon its shaft,) and also the pivoted pallet e^4 , such pallet being provided with a weighted pendulum-arm e^5 , as shown in Fig. 1. Movement of the circuit making and breaking wheel results in corresponding movement of the gear-wheel e and of the train in connection therewith and the consequent pivotal movement of the pal-

let e^5 . The retarding movement thus effected is of a character well known and well adapted to perform the function for which it is here designed.

The operation of my transmitter is as follows: When the transmitter is not in use, the switch-lever M is in the position shown in Fig. 1 and the circuit through the transmitter is broken. When it is desired to establish communication with any of the subscribers represented upon the dial of the transmitter or to give any of the signals indicated upon said dial, the knob F is turned through a complete revolution, thus causing the circuit making and breaking wheel to also turn through a complete revolution and to store sufficient power in the power-spring G to return the wheel to its normal or zero position. As the movement of the circuit making and breaking wheel in the direction to cause power to be stored in the power-spring is completed the stop d' , projecting from the lower surface of the circuit making and breaking wheel, contacts with the insulated frame m of the switch-lever M and moves such switch-lever in such a manner as to cause the arm m' of the same to contact with the contact-point m^4 and complete the circuit to the contact-lever L and through the transmitter. At this point also the pivoted pawl O enters the enlarged space before referred to between the two teeth d^2 and d^3 of the circuit making and breaking wheel. The indicator-plug K can now be inserted in the aperture corresponding to the connection desired to be established or the signal desired to be given. Upon the release of the knob F the power-spring G will cause the circuit making and breaking wheel to move in a reverse direction until the stop d , formed on the upper surface of the same, contacts with the lower end of the indicator-plug K. During the passage of the circuit making and breaking wheel through this movement the circuit is broken and made every time a tooth of the circuit making and breaking wheel passes the contact-lever L, and thus the receiver or other device with which the transmitter may be in electrical communication is properly actuated to establish the desired connection or set the desired signal. Upon withdrawal of the indicator-plug K the circuit making and breaking wheel will be returned to its normal or zero position by the power-spring G without the need of any operation on the part of the operator. As the circuit making and breaking wheel resumes its normal position the stop d' , projecting from the lower surface of the same, engages with the switch-lever M and breaks the circuit, and the pawl O falls again into the enlarged space between the two teeth of such circuit making and breaking wheel.

It is apparent that many changes or alterations can be made in the structure which I have herein disclosed without departing from

the spirit and scope of my invention, and I do not limit myself to the precise structural details shown; but

What I claim as new, and desire to secure 5 by Letters Patent, is—

1. In a transmitter, the combination with circuit-varying mechanism having an automatically-returned actuating member, and an indicator arranged to arrest the movement of 10 said actuating member at predetermined points, of a separate switch controlling the same circuit as said circuit-varying mechanism, means for reversing said switch when the actuating member reaches either extreme position of its movement, and a locking device 15 for preventing said actuating member from reversing its direction of movement at an intermediate point.
2. In a transmitter, the combination with 20 circuit making and breaking mechanism comprising a contact-brush, a toothed contact-wheel, means for rotating said wheel in one direction, and means for returning said wheel, of an indicator provided with openings

through which stops may be inserted to engage 2 said wheel and arrest the movement thereof, a separate switch controlling the same circuit as said circuit making and breaking mechanism, means operated by said mechanism for causing said switch to break its contact 3 through which said circuit passes when said actuating member reaches its normal position, and to complete said contact when said actuating member has reached the other extreme 3 of its movement, and a reversing-pawl, normally engaging the teeth of said wheel and preventing change of direction of motion thereof, said wheel having two teeth which are farther apart than the others, so as to permit the pawl to be reversed when such point 4 is reached.

In testimony whereof I affix my signature in presence of two witnesses.

ANTHONY VAN WAGENEN.
